UNITED STATES PATENT OFFICE.

GILBERT K. MONROE, OF SIDNEY, OHIO.

MOLD.

Application filed January 31, 1922. Serial No. 532,989.

To all whom it may concern:

Be it known that I, GILBERT K. MONROE, a citizen of the United States, residing at Sidney, in the county of Shelby 5 and State of Ohio, have invented certain new and useful Improvements in Molds, of which the following is a specification.

This invention relates to molds of the portable type for making pipes, tiling and 10 other similar cylindrical bodies from cement or similar materials and it relates particularly to molds of the type in which there is employed a collapsible core and an outer separable wall.

One of the objects of the invention is 15 to provide a structure of simple and effective form for supporting the mold proper during the pouring operation so arranged that it can be readily removed 20 from the mold after the pouring has been completed and immediately used for the purpose of supporting another mold for casting purposes; the molds proper being left intact about the casting until the curing 25 operation is completed.

A further object of the invention is to 30 provide in a supporting structure referred to, or outer jacket as it will be called, means for centering the walls of the mold therein, and for properly spacing said 35 walls with respect to each other; a more specific object in this connection being to provide an improved form of pallet for supporting and spacing the lower ends 40 of the mold walls, and also to provide means on the outer jacket operable to center the core when the jacket is closed about the mold.

A further object of the invention is to 45 provide improved means for expanding the core and holding the same in expanded position during the pouring and curing of the casting.

A further object of the invention is to 50 provide a mold construction which will be simple in construction, effective in operation and economical in manufacture and use.

In the accompanying drawings:

Fig. 1 is a top plan view with the mortar board removed.

Fig. 2 is a view of one side of the structure.

Fig. 3 is a view of the opposite side 55 of the same.

Fig. 4 is a bottom plan.

Fig. 5 is a vertical section.

Fig. 6 is a transverse section on the line 6—6 of Fig. 2.

Fig. 7 is a top plan showing the manner of removing the outer jacket.

Fig. 8 is a top plan showing the mortar board and trowel in position.

Fig. 9 is a perspective view of the trowel.

Fig. 10 is a vertical section of the upper portion of the structure showing the mortar board and trowel.

Fig. 11 is a perspective view of the mortar board.

Fig. 12 is a top plan of a portion of one of the core expanding rings.

Fig. 13 is a section on the line 13—13 of Fig. 12.

Referring to the drawings, 1 represents the inner wall or core of the mold, formed of a single piece of sheet metal bent to cylindrical form, the side edges of which overlap as shown in Fig. 6. The outer wall of the mold proper is indicated at 2, 80 and this wall is likewise formed of a single piece of sheet metal bent to cylindrical form, the side edges of which have connected therewith aligned eyes 3 of sheet metal to receive a removable rod 4 to 85 thereby temporarily hold the wall 2 in cylindrical form. The outer jacket is formed of two sheet metal sections 5 and 6 having two of the side edges hinged together by the hinges 7 and the other edges provided with devices whereby the jacket may be contracted and expanded. One set of these devices is located at the top and another set at the bottom of the jacket and each consists of a lever 9^a, pivotally connected with a U-shaped reinforcing ring 8 with which the jacket sections are preferably provided and having pivotally connected therewith a short distance from its pivotal point a link 9, having a notch 10 on its inner side near the outer end thereof whereby the link may be engaged with a pin 11 carried by the ring 8 on the other section 5. By manipulating the levers 9^a the jacket section may be 90 contracted or expanded.

Cooperating with the bottom of the outer jacket is a base ring or pallet 12 of T-shaped form in cross-section, as shown in Fig. 5. The outer edge of the horizontal portion of 110 the pallet is clamped against the lower edges of the jacket section and their lower rein-

forcing rings by flanged nuts 13, screwed on threaded stems 14, which project from the lower ends of metal vertically-disposed reinforcing straps 15, secured to the jacket 5 sections; the threaded stems being projected through the horizontal portions of the bar 8. The vertical portion of the pallet forms a rest for the structure. The outer wall 2 rests upon the horizontal portion of the pallet and to support the core the pallet has a series of fingers 12^a, which project inwardly from the vertical part of the pallet in a horizontal plane below that of the horizontal part of the pallet.

15 For the purpose of expanding the core, there are two preferably U-shaped split expanding rings 16 employed. Each of these rings has pivoted thereto near its ends a pair of substantially L-shaped levers 17 which 20 are in turn pivoted together at the points of the juncture of the arms of the respective levers, by the pin 18. To hold the rings in contracted position a short rod 19 is pivoted to one lever 17 of a pair and has a hook 20 25 to engage an eye 21 on the other lever of the pair, the hook being disengaged from the eye before the levers are manipulated to expand the ring against the inner wall of the core. The limit of expansion of the 30 bottom of the core is determined by the inner edge of the horizontal portion of the pallet, while the limit of expansion of the upper end of the core is determined by a ring 22 which is placed over the upper edge 35 of the core and has an inwardly projecting horizontal flange 23 to form a supporting shelf for a mortar board 24; the board having downwardly projecting lips 25 fitting the inner edge of the shelf to hold the 40 board in position; one of these lips being placed between the inwardly extending lugs 22^a (Fig. 1) and another lip against the opposite lug 22^b to keep the board from turning. A trowel 26 45 has on its rear side an eye 27 which may be loosely fitted over the vertical stem 28 of the mortar board, the outer end of the trowel having a handle 29 and a portion 26^a bent at right-angles to the main portion 26 and 50 lying immediately above the upper edge of the outer wall 2 when the trowel is in working position. The trowel extends across the board on a line passing at one side of the center of the board so that the effect of 55 the rotation of the trowel is to sweep the material into the molding space.

To center the upper portion of the core when the jacket is contracted, the upper reinforcing ring 8 of the jacket section carries 60 a series of centering devices, each consisting of a horizontal finger 30 having a vertical shank 31, square in cross-section and having a reduced rounded extension 32. The shank lies in a square opening 33 in the 65 upper horizontal portion of the top ring 8

while the extension 32 projects through a round opening in the lower horizontal portion of the ring. Before the core and outer wall of the mold are inserted in the jacket, these fingers stand at right-angles to the 70 position shown, but after the insertion of the core and wall, the fingers are turned to the position shown by lifting their shanks from the square openings 33, giving the 75 fingers a quarter turn and again placing the shanks in the openings, so that when the jacket is contracted the fingers will engage the ring 22 and thus center the upper portion of the core in the outer wall 2.

The parts are assembled for the purpose 80 of making a casting by first attaching the base ring or pallet to the lower edge of the jacket by placing the outer horizontal portion of the pallet under the flanges of the nuts 13 and then tightening the nuts. The latches 9 are then engaged with the pins 11, and the levers 9^a turned to contract the jacket. Next, the collapsible core is inserted in the jacket with its lower end resting on the projecting fingers 12^a inside of the inner 85 edge of the horizontal portion of the pallet. One of the expandable rings is then inserted in the core near the lower end thereof and expanded and the other expandable ring inserted in the core near the upper end therefore but left temporarily contracted. The ring 22 is then inserted over the upper end of the core. The outer wall 2 of the mold is then inserted in the jacket, first expanding the top of the jacket by manipulating the 90 upper lever 9. The centering fingers 30 at the top of the jacket are then turned to position and the upper end of the jacket contracted or closed which causes the fingers to contact the ring 22 and center the core. The 95 mortar board is then placed on the top of the core retaining ring 22 and the trowel inserted on the board. The material forming the casting is placed on the mortar board and by then rotating the trowel the material 100 is fed to the space between the core and outer wall of the mold.

After the casting has been completed the 105 entire structure, minus the mortar board and trowel, is removed to the curing place. The jacket is then removed by manipulating the levers to expand its walls, the extreme ends of the links 9 being placed against the pin 11 to assist in separating the jacket from the inner wall, if necessary. The ring 22 may 110 also be removed. The rest of the structure is left intact to permit the material of the casting to cure or set. After setting, the mold is turned upside down and the pallet removed. The core expanding rings are then released 115 and removed and the core contracted and removed. The pintle or rod 4 is removed from the eyes on the outer wall and this wall removed.

120 By the construction described it will be 130

seen that a master jacket or supporting structure is provided which serves the purpose of supporting the mold proper consisting of the inner core, outer wall, supporting 5 base ring, upper retaining ring and core expanding rings, which master jacket may be removed as soon as the pouring of the casting is complete and may be used with another set of mold parts. This furnishes an 10 economical and simple molding apparatus, for the parts of the apparatus other than the jacket may be of the simplest construction which may be duplicated in sufficient number at a comparatively small expense to 15 make a large number of castings.

By the peculiar construction of the base ring described, including the supporting fingers for the core, any material which leaks by the horizontal portion of the casting falls 20 to the ground instead of accumulating and hardening on the ring, thus obviating the necessity of cleaning the ring. By the construction of the core described it may be adjusted to different diameters to adapt it 25 to different sized molds or to regulate the thickness of the walls of the casting.

The mold structure described is adapted for operation on the line of the ditch in which the tiling is to be used and may receive any suitable form of reinforcement for 30 the material, as the tile may be molded from quite wet plastic material, but which may be puddled or spaded in the mold to obtain a smooth surface and eliminate air pockets.

35 Having thus described my invention, I claim:

1. In a structure of the character described, inner and outer independent walls forming a molding space, an outer retaining 40 member, and means carried by said member for supporting said walls in spaced relation with each other.

2. In a structure of the character described, inner and outer independent walls forming a molding space, an outer retaining 45 member, and means carried by said member for supporting said walls in spaced relation with each other, including a base ring to form a bottom for the molding space.

50 3. In a structure of the character described, inner and outer independent walls forming a molding space, an outer retaining member, and means carried by said member for supporting said walls in spaced relation with each other, including a plurality of fingers to engage the upper portion of the inner wall.

4. In a structure of the character described, inner and outer independent walls forming a molding space, an outer jacket, 60 together with means for clamping the same to the outer wall, a base ring carried by said jacket to support the lower ends of said walls in spaced relation and to form a bottom for the space between said walls, and fingers car-

ried by the upper part of said jacket to engage the upper end of the inner wall to center the same within the outer wall.

5. In a structure of the character described, the combination of an inner expandable core together with means for holding the same in expanded position, an outer wall cooperating with the core to form a molding space, an enclosing jacket for said core and wall, a base ring detachably connected with said jacket and arranged to support the core and wall in spaced relation with each other and forming a bottom for the molding space, means for clamping said jacket to said outer wall, and means carried by said jacket for centering the upper end of said core in said outer wall. 70

6. In a structure of the character described, the combination of an inner expandable core formed of a single piece of sheet metal bent to cylindrical form, an outer wall cooperating with said core to form a molding space, an enclosing jacket for said parts having means for clamping the same to said outer wall, and means carried by said jacket for supporting and spacing the lower ends of said core and wall, a ring enclosing the upper edge of said core, means for expanding said core, and means carried by said jacket and engaging said ring for centering the core within said wall. 85

7. In a structure of the character described, the combination of an inner expandable core formed of a single piece of sheet metal bent to cylindrical shape, an outer wall cooperating with said core to form a molding space, an enclosing jacket for said parts including means for clamping the same against the outer surface of said wall, a base ring removably attached to the lower end of said jacket, said ring having a horizontal portion and a vertical portion and also having a series of supporting fingers projecting inwardly therefrom in a plane below said horizontal portion, said core being supported by said fingers and said wall supported by said horizontal portion of said ring, and means carried by said jacket for centering the upper portion of 100 said core. 105

8. In a structure of the character described, inner and outer independent removable walls forming a molding space, an outer retaining member formed of two sections hinged together at two adjacent sides, means carried by the other sides for contracting said member about said outer wall, and means carried by said member for supporting said walls in spaced relation. 110 120

9. In a structure of the character described, inner and outer walls forming a molding space, an outer jacket formed of two sections hinged together at two adjacent side edges, a plurality of levers carried 125 130

by one of said sections at the other side edges, a link pivoted to each lever near its pivotal point, engaging means for said link on the other section, and means carried by 5 said jacket for supporting said walls in spaced relation.

10. In a structure of the character described, inner and outer cylindrical independent walls forming a molding space, 10 means for holding said walls in spaced relation, a mortar board supported on the upper edge of said inner wall and terminating at a point adjacent the space between said walls, and a revoluble member carried 15 by said mortar board and projecting to a point over the space between said walls for feeding material to the molding space as the same is revolved.

11. In a structure of the character described, inner and outer cylindrical walls forming a molding space, means for holding said walls in spaced relation, a mortar board carried by the upper end of the inner

wall and terminating at a point adjacent the space between said walls, a revoluble trowel 25 on said mortar board and projecting to a point adjacent the top edge of the outer wall, the outer end of said trowel having a bent end projecting in the direction of travel of said trowel as it is revolved upon said board.

12. In a structure of the character described, inner and outer cylindrical walls, means for supporting said walls in spaced relation to each other, said inner wall consisting of a single piece of sheet metal, and a plurality of expansible devices to expand said inner wall, each device consisting of a split ring and a pair of levers pivotally connected to said ring, one on each side of 40 the split therein and also pivotally connected together at intermediate points.

In testimony whereof, I have hereunto set my hand this 28th day of January, 1922.

GILBERT K. MONROE.
